NONCRUSHING SLIDER

Louis H. Morin, Bronx, N. Y., assignor to White-hall Patents Corporation, Bronx, N. Y., a corporation of New York

Application November 28, 1938, Serial No. 242,736

4 Claims. (Cl. 24—205)

This invention relates to sliders of slide fasteners employing stringers coupled and uncoupled by the movement of the slider longitudinally thereof. More particularly the invention relates 5 to the construction of the pivot post or lug on the top wall of the slider and with which the pull is pivotally connected in such manner as to provide, as a continuation of or part of this lug, a raised reinforcing body disposed directly 10 over the connecting web joining top and bottom walls of the slider so that any crushing strains to which the upper surface of the slider may be subjected is taken up by said raised reinforcing body and not transmitted to the upper wall of 15 the slider which would otherwise tend to crush or distort the slider, jamming the same upon the stringers or otherwise rendering the same inoperative. The novel features of the invention will be best understood from the following description 20 and annexed drawing, in which one embodiment of the invention is disclosed and in which the separate parts of the device are designated by suitable reference characters in each of the views, and in which:

25 Fig. 1 is a plan view of a part of a slide fastener showing a slider thereon with part of the construction broken away.

Fig. 2 is a longitudinal sectional view through the slider shown in Fig. 1, detached and diagrammatically illustrating the same between two surfaces.

Fig. 3 is a side view of the slider shown in the normal cast position thereof and prior to the attachment of the finger piece or pull there- 35 with, and

Fig. 4 is a view similar to Fig. 2 showing a conventional form of slider and illustrating the effect of a crushing strain or force applied thereto.

40 In sliders of the type and kind under consideration where a pivot post or lug is provided on one surface of one of the side walls of the slider for the attachment or pivotal support of a finger piece or pull therewith, such sliders have 45 been subjected to distortion or crushing rendering the same inoperative and actually destroying the complete fastener. To illustrate one of such sliders, I have shown in Fig. 4 of the drawing a slider 5, the top wall 6 of which is provided with a pivot lug or coupling 7, in connection with which the pivot end 8 of a finger piece or pull 9 is mounted. One slider having a finger piece or pull mounting of this general type and kind is illustrated, for example, in Patent 55 #2,123,512, granted July 12, 1938. With this

type of device, when applied to certain types of garments which are subjected to pressing or otherwise subjected to a pressure applied to the upper surface or wall of the slider, the downward pressure, for example of a surface such as indicated in dot and dash lines at 10, would engage the upwardly projecting stud 7 which is usually arranged centrally of the slider and would tend to force the free end of the top wall 6 downwardly in the direction of the bottom wall 6a, as is highly exaggerated by the dotted line illustration of the wall 6 in said figure. It will of course be understood that the links of the fastener stringers are disposed between the walls. 10 However, this downward pressure I have found from experience, would tend to jam the slider upon the stringers and would at least momentarily render the fastener inoperative. This is especially true in placing garments in pressing machines where considerable pressure is applied 15 in the pressing or creasing of garments.

To overcome this objectionable feature in fastener devices which are applicable to garments or other supports subject to pressure on the upper surface thereof, I have provided a slider such 20 as shown in Figs. 1 to 3 inclusive, comprising a slider body 11 having top and bottom walls 12, 13 joined at one end by the usual substantially V-shaped connecting web 14. With this construction I provide a pivot lug consisting of a 25 large and long reinforcing body part 15 and a substantially hook-shaped part 16 between which is a recess 17 which is normally open in the initial formation of the slider as is seen in Fig. 3 of the drawing, so as to permit the arrangement 30 of the pivot crosshead end 18 of a finger piece or pull 19 in the recess 17 prior to closing the hook 16 as is shown in Fig. 2 of the drawing.

The body 15 extends longitudinally of the top 40 wall of the slider to the wide end portion thereof and is arranged directly above the connecting web 14 with the upper surface 15a of the body 15 arranged above the upper surface of the hook 16 when in its closed position, as is clearly seen 45 in Fig. 2 of the drawing, so that in the pressure movement of a surface as at 10a of, for example, the board or plaque of a pressing machine, in the direction of the upper surface of the slider 11, the thrust will be taken directly upon the body 15 and transmitted through said body and 50 the connecting web 14 to a lower supporting surface or table 10b, as is diagrammatically illustrated in Fig. 2 of the drawing, so that no crushing effect will take place upon the top wall 12 or no tendency will prevail to force or tilt the same 55

upon the links 20, 20a of the separable fastener stringers 21, 21a, parts of which are shown in Fig. 1 of the drawing.

- It will also appear from a consideration of Fig. 5 1 of the drawing that the reinforcing or crush-resistant body 15 of the slider is preferably made of the same width as the width of the hook-shaped part 16 so as to form a neat and finished appearance on the top of the slider, and further 10 to keep the body 15 substantially within the boundaries of the connecting web 14, it appearing from Figs. 2 and 3 of the drawing that the length of the body 15 is substantially equal to the length of the web 14, so that no strain will 15 be transmitted to the top wall 12 when the surface 10a is moved under pressure in the direction of the surface 10b with a slider therebetween.

In order to perform the desired function in a 20 slider of the character under consideration, it is essential that the non-crushing body be disposed and localized at the wide end of the slider and above the connecting web, showing the top and bottom walls of the slider, and further in 25 forming a more or less solid wall structure through the depth of the slider at this particular section or area. I am well aware of the fact that sliders have been made wherein a rib or channel has extended longitudinally of the upper 30 wall of the slider, but in such cases, the outer surfaces of the rib have had the same spacing throughout the length of the rib and therefore the weakened contracted end of the slider has been subjected to the stress or strain and would 35 be compressed onto the links of the stringer to jam the slider thereon and not perform the function which is successfully performed with my improved slider construction.

It will also be apparent that the finger piece 40 or pull 19 is provided with a large opening 22 at the pivot end portion 18 thereof so as to permit the pull to be moved into either of the depressed positions illustrated in full and in dotted lines in Fig. 2 of the drawing, so that the parts 15 and 16 will be cleared by the pull and to maintain the pull well below the upper surface 15a of the reinforcing non-crush body 15 of the slider. It will of course be apparent that my invention is applicable to sliders having 45 different forms of mountings of the finger pieces and pulls in connection therewith, and in the present construction it will be apparent that the body 15 forms part of the pivot lug on the pull. That is to say, the wall 15b defines part 50 of the boundary walls of the aperture or recess 17 receiving the pivot pin 18 of the pull, and the pull engages the wall 15b in the movement of the slider along the stringers in the operation of coupling the links 20, 20a. It will thus be 55 seen that the body 15 also forms a strong or well reinforced backing to resist the stress or strain of the pull upon the slider in the operation of closing the fastener.

Having fully described my invention, what I 60 claim as new and desire to secure by Letters Patent, is:

1. A non-crush slider for separable fasteners of the character described, said slider comprising top and bottom walls having narrow and wide end portions, said walls being joined and spaced at the wide end portion by a connecting web, the top wall having integral means on the

outer surface thereof for coupling a finger piece or pull therewith, said means comprising a hook-shaped member arranged upon the narrow end portion of said wall and an enlarged solid reinforcing body arranged upon the wide end portion 5 of said wall, the upper surface of said body being arranged above the upper surface of said hook-shaped member, said body forming in conjunction with said member a recess for receiving the finger piece or pull, and said body extending longitudinally of the slider and directly above and in registering alignment with said connecting web so that pressure applied to the upper surface of said slider will be taken up directly through said body and web. 10

2. A non-crush slider for separable fasteners of the character described, said slider comprising top and bottom walls having narrow and wide end portions, said walls being joined and spaced at the wide end portion by a connecting web, 20 the top wall having integral means on the outer surface thereof for coupling a finger piece or pull therewith, said means comprising a hook-shaped member arranged upon the narrow end portion of said wall and an enlarged solid reinforcing body arranged upon the wide end portion 25 of said wall, the upper surface of said body being arranged above the upper surface of said hook-shaped member, said body forming in conjunction with said member a recess for receiving 30 the finger piece or pull, said body extending longitudinally of the slider and directly above and in registering alignment with said connecting web so that pressure applied to the upper surface of said slider will be taken up directly through 35 said body and web, and said body and hook-shaped member being of substantially the same thickness.

3. A slider for separable fastener stringers of the character described comprising top and bottom walls joined and spaced apart by a connecting web arranged centrally of one end portion of the slider, the top wall of the slider having two solid members integral with and projecting upwardly from the outer surface of said wall, one of 40 said members being disposed directly over said connecting web and being of a length substantially equal to the length of said web, the other member being arranged adjacent the other end portion of said wall and having a curved free 45 end portion extending in the direction of the first named member and forming in conjunction with the first named member of the slider a pull receiving recess, and the upper surface of said, first named member being arranged above the 50 upper surface of the hook-shaped member whereby pressure applied to the upper surface of the slider will be taken up directly through 55 said member and connecting web.

4. In a slider having spaced walls joined at 60 one end by a connecting web, means on the outer surface of one wall of the slider for coupling a pull therewith, said means being arranged on said wall in spaced relation to said connecting web, a solid reinforcing body integral with said 65 wall of the slider directly over and in alignment with said web, and the upper surface of said body being arranged above the upper surface of said pull supporting means whereby pressure applied to the slider will be transmitted directly 70 through said body and web.
